(57) **CLAIM**

The ornamental design for a display screen or portion thereof with graphical user interface, as shown and described.

DESCRIPTION

FIG. 1 of the drawings is a first image in a sequence of the display screen or portion thereof with graphical user interface showing, in particular, the ornamental design thereof; FIG. 2 of the drawings is a second successive image thereof; FIG. 3 of the drawings is a third successive image thereof; FIG. 4 of the drawings is a fourth successive image thereof; FIG. 5 of the drawings is a fifth successive image thereof; and,

FIG. 6 of the drawings is a sixth successive image thereof. The outer edge of the portion of the display screen is understood to be congruent with the outer edge of the graphical user interface.

The appearance of the animated image sequentially transitions between the images shown in FIGS. 1 through 6. The process or period in which one image transitions to another forms no part of the claimed design.
